UNITED STATES PATENT OFFICE

GUSTAF S. BECKMAN, OF CRANSTON, RHODE ISLAND, ASSIGNOR TO UNIVERSAL WINDING COMPANY, OF BOSTON, MASSACHUSETTS, A CORPORATION OF MASSACHUSETTS

SLUG CATCHER OR YARN CLEANER

Application filed June 8, 1926. Serial No. 114,562.

This invention relates to an improved slug-catcher or yarn-cleaner for use with textile machines for removing slugs, bunches, motes, or other foreign matter from thread or yarn during the process of winding or otherwise transferring the material.

The principal object of the invention is to provide a slitted or slotted member through which the yarn or thread draws to scrape enlargements or foreign matter therefrom with said member operated automatically by the movement of the strand feeding through the slit to dislodge the lint, dust and other particles collected thereon.

15 A particular object of the invention is to provide a slug-catcher of the type specified which is vibrated or oscillated under the swaying action of the strand drawing therethrough, whereby the yarn slides in the slit or opening to prevent it from wearing grooves in the sides thereof, and also to push out the lint and other particles and to shake off or dislodge the accumulation which may collect thereon.

20 Further objects of the improvement are set forth in the following specification which describes a preferred embodiment of the invention as illustrated by the accompanying drawings. In the drawings:

25 Fig. 1 is a view showing a portion of a winding machine and its yarn-tensioning means and illustrating the present improved slug-catcher as applied to use therewith;

30 Fig. 2 is a plan view of the same showing the thread-guide which traverses the yarn or other strand material on the package being wound and illustrating the manner in which the strand leads from the tension-device through the slug-catcher and thence to the thread-guide;

35 Fig. 3 is an enlarged end view of the slug-catcher shown in connection with the tension-device;

40 Fig. 4 is a detailed view of the main slug-catcher member;

45 Fig. 5 is a perspective view of the same looking in the opposite direction; and

50 Fig. 6 is a similar perspective view showing the parts of the slug-catcher in disassembled relation.

55 My improved slug-catcher or yarn-cleaner comprises essentially a slitted or slotted member which is mounted to adapt it to vibrate or oscillate back and forth under the action of the strand drawing through its slit or opening, whereby as it scrapes the foreign matter off from the yarn the movement of the strand in the slit will push the accumulation out of the slit and the vibration of the member will act to shake it off.

60 Figs. 1 and 2 of the drawings illustrate a conventional type of drum-winding machine for winding conical packages of yarn or thread with the material laid in crossing coils thereon. As illustrated in these views, 2 designates the cylindrical drive-roll or friction-drum and 3 is the conical mandrel or cone-holder on which the package is wound. The cone-holder 3 rests against the surface of the drive-roll or friction-drum 2 at the start of 65 the winding and the yarn, thread or other attenuated material *y* is fed between the drum and the holder and traversed longitudinally thereof by means of a reciprocating thread-guide 4. During the winding the drive-roll 70 2 is continuously rotated from its shaft 5 and the cone-holder or mandrel 3 is supported to adapt the cop or cone to contact therewith to be driven therefrom, with the holder receding from the roll as the yarn is built up 75 on the package.

80 The thread-guide 4 slides on a horizontal rod 6 and is reciprocated from a suitable cam 7 having a helical groove engaged by a stud or roller 8 connected with the guide. As 85 these elements of the winding-mechanism are of well-known construction and arrangement they are not herein shown and described in detail.

89 In winding machines of the present type 90 it is usual to apply tension to the strand *y* as it draws from its supply and feeds to the thread-guide 4, and the reference numeral 10 indicates in general a preferred form of tension-device for this purpose. As herein illustrated the tension-device 10 is supported on an arm or bracket 11 which is bolted to an extension 12 forming a part of the winding machine frame. The arm or bracket 11 has a horizontally disposed shelf or rest 13, on 95 100

which is mounted the lower tension disk 14 which cooperates with an upper disk 15 of the same form. The disks 14 and 15 are of usual construction, having their abutting faces substantially flat and their peripheral edges flaring outwardly to adapt the strand to be drawn into place between them. The disks 14 and 15 have axial bores through which extends a vertical stud or pin 17 projecting upwardly from the shelf 13 of the bracket 11 and held at the top in an ear 18. The ear 18 forms a part of an arm or guard-member 20 which is attached at 21 to the horizontal rest 13 on the bracket 11, see Fig. 2.

The guard-member 20 has a circular rim 22 which is contiguous to the outer rim of the shelf or rest 13 with its lower edge spaced slightly above the upper face thereof. Projecting upwardly at an angle from the rim 22 is a finger or prong 23 which is disposed to cross a similarly-shaped prong 24 reaching upwardly from one side of the shelf or rest 13. The prongs 23 and 24 provide guiding-means for directing the strand *y* down under the circular rim 22 of the guard 20 whereby it may be drawn into place between the faces of the two tension-disks 14 and 15.

Slidable on the vertical pin 17 of the tension-device is a shouldered sleeve 26 adapted to carry weights 27 which act to press the upper tension-disk 15 down against the lower disk 14. The particular arrangement of the tension-device 10 as above described forms the subject-matter of a separate application and has no direct relation to the present invention. That is to say, the tension-device is herein illustrated merely to show the method in which the present improved slug-catcher operates in connection therewith, but the present invention is also adapted for use with other forms of tension-means.

In the present embodiment of the invention the slug-catching or yarn-cleaning element 30 is constructed of sheet-metal parts and pivotally mounted on a wire or rod 31 supported from the arm or bracket 11 for the tension-device 10. Conveniently, the rod 31 may be screwed into a threaded hole 32 in an ear or lug 33 which projects downwardly from the under side of the shelf or rest 13. A check-nut 34 on the rod 31 is screwed up against the side of the lug 33 to fixedly secure the rod in the position as illustrated in Figs. 1 to 3. The outer end of the rod 31 is bent into a right-angled arm 35 which is bent around again in the extension 36 disposed parallel with and offset from the main portion of the rod. The slug-catcher 30 is pivotally mounted on the rod 31 between its crook or bent arm 35 and the nut 34 to adapt it to rock back and forth on a horizontal axis.

Referring now particularly to Figs. 5 and 6, the slug-catcher 30 as herein illustrated comprises two connected members 40 and 41.

Referring to Fig. 6, the main member 40 is constructed with a lower horizontal strip 42 having an upwardly bent circular ear 43 at its end which is provided with a hole or aperture 47 for receiving the pivot-rod 31. At its opposite end the strip 42 is bent upwardly at right-angles in an arm 48 having a hook-like extension 49 at its end. The arm 48 is provided at its lower end with an aperture 50 arranged in line with the aperture 47 in the ear 43 and serving as a second pivotal bearing for receiving the rod 31. A right-angled extension 51 on the side of the arm 48 is bent back in a finger 52 which bows upwardly above the aperture 50 and is formed with a bent-over lug or stop 53 at its end. A threaded hole 54 extends through the doubled-over or folded portion of the extension 51, and on the opposite side of the arm 48 is a hooked finger or stop-lug 55.

The other element 41 of the slug-catcher consists of a sheet-metal member having a vertical arm 56 conforming to the shape of the arm 48 on the main member 40, but with its hooked end extending in the opposite direction. The lower portion of the member 41 consists of a slotted strip 57 which is slightly offset from the vertical plane of the arm 56. The strip 57 is adapted to overlie the right-angled extension 51 of the arm 48 on the main member 40 with its slot 58 enclosing the pivot-rod 31, see Figs. 3 and 5. A screw 59 extends through a second slot 60 in the member 41 and is screwed into the hole 54 in the member 40 to secure the parts of the slug-catcher in fixed relation. The slot 58 serves to hold the member 41 with its arm 56 in parallel relation with respect to the arm 48 on the member 40, see Fig. 5, their opposite edges being spaced apart to form the slit or opening for the yarn. By releasing the screw 59 the member 41 may be slid on the member 40 to adjust the width of the opening or slit between the edges of the arms 56 and 48 in accordance with the size or thickness of the yarn to be operated upon. It is to be particularly noted that the adjacent edges of the arms 48 and 56 are notched or cut away at their lower ends whereby, when the arms are adjusted in opposite relation as shown in Fig. 5, a circular opening 61 is provided for the escape of lint, dirt or other foreign matter gathered by the cleaning edges of the slug-catcher and scraped or pushed downwardly in the slit by the action of the yarn as it plays along these edges in the manner as herein-after more fully explained.

Referring now particularly to Figs. 3 and 4 of the drawings, when the slug-catcher 30 is mounted on its pivot or bearing-rod 31 by means of its apertures 47 and 50 it is free to rock to carry its slit or opening back and forth across the vertical plane of its axis. When the member 30 swings to the right, as viewed in Fig. 3, the stop-lug 55 will bring

up against the outer crooked portion 35 of the rod 31 to limit its tilting motion in this direction; while, on the other hand, when the member 30 rocks back in the opposite direction, as illustrated in Fig. 4, the stop-lug 53 on the finger 52 will strike the top of the bent portion 35 of the rod 31 to limit its swinging motion in this direction.

As the strand y of yarn, thread or other material draws through the tension-device 10 in a substantially horizontal course it will lead through the slit or opening between the arms 56 and 48 of the slug-catcher 30 in the manner as shown in Fig. 1, and means are provided for holding the yarn substantially in this path to prevent it from rising up out of the slit in the slug-catcher. In the present embodiment of the invention this means consists of a drop-wire or stop-lever 62 which forms a part of the stopping-mechanism of the winding machine herein illustrated. The drop-wire 62 may consist of a wire arm or lever which, as shown in Figs. 1 and 2, is pivoted to a cross-rod 63. The outer end of the lever 62 is formed with a hooked portion 64 having a horizontal cross-bar 65 under which the strand y normally draws. The cross-bar 65 is bent downwardly at its end in a curved abutment 66 which prevents the yarn from riding off therefrom, and a portion 67 of the wire is then extended upwardly in an inclined hook which serves as a guard or guide to direct the yarn down in under the cross-bar, see Fig. 3.

It will be understood that the drop-wire or stop-lever 62 is normally suspended in raised position by the strand y passing under its cross-bar 65 and the outer end 36 of the rod 31 serves as a stop to prevent the drop-wire from being lifted to a further extent, see Fig. 1. When the strand y breaks or its supply is exhausted the drop-wire 62 will be released, whereby its outer end will swing downwardly under the action of gravity to set in motion the stopping-mechanism which arrests the operation of the winding machine. The stopping-mechanism of the machine is not herein described or illustrated as it forms no part of the present invention and may be of any conventional type. The yarn y is prevented from being released or dropping out of the bottom of the slit in the slug-catcher 30 by the cross-member or finger 52, the edge of which will be engaged by the yarn as it slides down in the slit.

The yarn y draws from the drop-wire or stop-lever 62 across a thread-bail 70, see Fig. 1, and thence leads through the eye in the thread-guide 4. The thread-bail 70 is usually arranged to be operated to lift the yarn out from the thread-guide when the winding of the package is arrested, but as the arrangement and method of operation of this device has no relation to the present invention it is not herein shown or described.

The improved slug-catcher operates in the following novel manner to secure a more efficient cleaning of the yarn, thread or other strand material. It has been explained that the yarn y is threaded through the tension-device 10 and thence drawn through the slit or opening in the slug-catcher 30, the hooked ends of the arms 48 and 56 providing a reentrant guideway for facilitating the threading of the strand into the slit. From the slug-catcher 30 the yarn y leads under the cross-bar 65 of the drop-wire 62 and draws across the thread-bail 70 and through the thread-guide 4, its end being attached to the mandrel or cone-holder 3. As the winding machine operates to wind the yarn or thread on to the cone-holder 3 the thread-guide 4 traverses the strand back and forth from one end of the cop to the other as indicated by the full and dotted lines in Fig. 2 which show the thread-guide at the extremes of its traverse.

The member 41 of the slug-catcher 30 is adjusted on the member 40 in such relation that the size of the slit or opening between the arms 48 and 56 will permit the yarn to pass freely therethrough, but with the edges of the opening bearing lightly against the sides of the yarn. In this way the slug-catcher acts to scrape and clean the yarn to remove any enlargements, bunches, slugs, motes, lint, dirt or other foreign matter which may be present in the cotton or other material. This foreign mater is usually collected in the slit through which the yarn draws and it may eventually build up into a hard mass and become compacted to such an extent that it will clog the slit and prevent the yarn from drawing freely therethrough. Moreover, when a certain amount of lint and dirt has collected in and around the slit it will have a tendency to adhere to the yarn and therefore the slug-catcher will lose its efficiency for thoroughly cleaning the material. In the improved device as herein shown and described accumulation of fluff, lint and dirt in and around the slit of the slug-catcher 30 is prevented by the action of the yarn which sways back and forth during its traverse by the thread-guide and is also caused to play up and down in the slit to scrape and clear the collected matter therefrom. That is to say, as the thread-guide 4 reciprocates between the extremes of its traverse the strand y will be vibrated or swayed back and forth from a to b as indicated in Fig. 2. This traversing motion of the strand y is therefore communicated to the slug-catcher 30 to cause the latter to rock back and forth between its extremes of position as illustrated in Figs. 3 and 4 of the drawings.

The thread-guide 4 reciprocates at a high rate of speed and consequently the swaying yarn imparts a very rapid oscillation to the slug-catcher 30 to maintain it constantly in

motion. As it swings back from one extreme of throw to the other its stop-lugs 53 and 55 strike sharply against the end 35 of the rod 31 and the lint and other particles are dislodged and shaken off so that the parts are kept free of accumulation.

During the rocking or oscillation motion of the slug-catcher 30 the yarn travels or slides lengthwise of its slit or opening due to its being held in a mean horizontal position as it draws from the tension 10 in under the stop-lever 62. That is to say, since the path of the yarn between the tension-device and the stop-lever 62 remains in substantially the same horizontal plane the rocking of the slug-catcher 30 will cause a relative radial movement of the yarn toward and away from its axis of oscillation. It will thus be seen that since the yarn has this sliding motion along the slit in the slug-catcher 30 it will be prevented from wearing or cutting grooves in the edges of the slit, and further, it will have a tendency to push the lint and dirt down through the slit to cause it to escape through the opening 61 at the bottom thereof. This sliding action of the yarn in the slit of the slug-catcher thus augments the cleaning action due to the vibratory motion of the latter, which acts of itself to dislodge and shake off the particles of lint and other foreign matter. It has been demonstrated that this peculiar action between the yarn and the slug-catcher maintains the slit in the slug-catcher substantially clear of lint, dirt and other accumulation, thus preventing it from being clogged to hinder the proper action of the device while keeping all of the parts clean. The improved slug-catcher is therefore rendered more efficient for the purpose described and is also less liable to wear and deterioration so that it is more durable in use.

While I have herein illustrated and described a preferred form of construction of the device it is obvious that various modifications may be made in the structure and arrangement of its parts without departing from the spirit or scope of the invention.

Therefore, without limiting myself in this respect, I claim:

1. A slug-catcher or yarn-cleaner for operating on a longitudinally and laterally moving strand comprising an element having a slit through which the strand draws and adapted to be oscillated transversely of the path of travel of the strand under the lateral movement of the latter whereby the strand is caused to slide longitudinally of the slit to prevent the accumulation of lint and foreign matter therein.

2. A slug-catcher or yarn-cleaner for operating on a longitudinally and laterally moving strand comprising a slotted member movably mounted to adapt it to be oscillated transversely of the direction of feed of the strand under the lateral traversing motion

of the latter as it draws through the slit whereby the strand is caused to continuously slide in the slit to prevent the accumulation of lint, fly and foreign matter on the member.

3. A slug-catcher or yarn-cleaner for operating on a longitudinally and laterally moving strand comprising a member having a slit through which the strand draws, and means for pivotally mounting said member to adapt it to oscillate back and forth on an axis substantially parallel with the course of the strand under the lateral movement of the latter whereby the strand is caused to slide back and forth in the slit to prevent the accumulation of lint and foreign matter therein. 70 75 80

4. In a slug-catcher or yarn-cleaner for operating on a longitudinally and laterally moving strand, the combination of a member having a slit through which the strand draws, means for pivotally mounting said member to adapt it to rock upon an axis substantially parallel with the course of the strand whereby the swaying action of the latter will oscillate the pivoted member and thereby cause the strand to slide longitudinally of its slit to prevent the accumulation of lint and foreign matter therein, and means for limiting the extent of rocking movement of said member on its pivot under the lateral traversing motion of the strand drawing through its slit. 85 90 95

5. An improved slug-catcher or yarn-cleaner for operating on a longitudinally and laterally moving strand comprising two members arranged in opposite parallel relation with an opening between their edges through which the yarn draws, means to adjust said members to vary the width of the opening, and means for movably mounting the members to adapt them to be oscillated transversely of the course of the yarn under the lateral traversing motion of the latter whereby the yarn is caused to slide longitudinally of the opening between the opposite members to prevent the accumulation of lint and foreign matter therein. 100 105 110 115

6. In a slug-catcher or yarn-cleaner for operating on a longitudinally and laterally moving strand, the combination of a member having spaced bearings to adapt it to be rockably supported and provided with an arm having a substantially straight edge, a second member adjustable on the first member and provided with an arm adapted to be set with its edge in spaced relation to the edge of the arm on the other member to form a slit through which the strand draws, and means for pivotally mounting said members as a whole to adapt them to oscillate transversely of the course of the strand whereby the latter will slide longitudinally of the slit through which it draws to prevent the accumulation of lint and other foreign matter therein. 120 125 130

7. In a device of the type specified for operating on a longitudinally and laterally moving strand, the combination of pivot-means, and a member rockably mounted on said pivot-means and provided with a vertical slit through which the strand of yarn or thread draws, said member being adapted to be rocked transversely of the course of the strand during the lateral traverse of the latter whereby the strand is caused to slide longitudinally of the slit to dislodge lint, fluff and particles of foreign matter scraped off from the yarn.

8. In a device of the type specified for operating on a longitudinally and laterally moving strand, the combination of a pivot-rod having an offset arm at its end, a slotted member rockably mounted on the rod, and means on said member adapted to engage the offset arm of the rod to limit the rocking motion of the member under the lateral traversing motion of the strand drawing through its slit.

9. In a device of the type specified, the combination of a rod, a member having spaced bearings for rockably mounting it on the rod, an upright arm on said member, a second member having an opening through which the rod extends and an upright arm adapted to be adjusted with its edge in spaced relation with respect to the arm on the first member, and means for securing the two members with their arms in fixed relation to provide a slit through which the yarn draws.

35. In testimony whereof I hereunto affix my signature.

GUSTAF S. BECKMAN.
